UNITED STATES PATENT OFFICE.

EDWARD A. FALL, OF RUTHERFORD, NEW JERSEY.

HEATING HOOD FOR TANK-CAR OUTLETS.

Application filed August 2, 1922. Serial No. 579,230.

The present invention relates to heaters for tank car outlets, and has for its object to provide means whereby the outlets of tank cars in which liquid or semi-liquid materials are transported may be readily heated and the outlets freed of any congealed or thickened deposits which may have collected in the outlets so that the flow from the car will be free and unimpeded.

- 10 In the transportation of certain materials, among which may be named asphaltum and similar bitumen products, difficulty has been experienced, particularly in cold weather, because of the material compacting and congealing, either because of low temperatures, or because of precipitation in the relatively narrow outlets which are ordinarily arranged at the base of the car, and through which the contents of the car is drained.
- 15 20 This difficulty has been so pronounced that it has been not unusual to build fires beneath the cars at the outlets to heat up the outlets and their contents so that the material can flow. This is dangerous, and disastrous fires have resulted, and invariably defacing and injury of the cars result from this practice.

It is with the object of providing an outlet heater which can be readily applied to the outlets of standard tank cars that I have devised the construction which will be hereinafter set forth, reference being had to the drawings forming part of this specification.

In the drawings:—

- 30 35 Fig. 1 is a view of so much of a tank car and car frame as is necessary to illustrate the application of my invention thereto.

Fig. 2 is a vertical sectional view on an enlarged scale of a tank car outlet with my heater applied thereto.

Fig. 3 is a top plan view of the heater shown in Fig. 2.

Fig. 4 is a view of a portion of a tank car with internal heating coils or pipes having a connection for the outlet heater.

Fig. 5 is a view of a slightly modified form of heater.

Fig. 6 is a detail view of a further modification.

50 Referring to the drawings by numbers, like numbers indicating like parts in the several views, 10 indicates a portion of the shell of a tank car and 11 indicates longitudinal bolsters of a car on which the shell 10 is suitably mounted.

The car outlet 12 is conventionally shown, and, as illustrated, comprises the down spout leading from the bottom of the car and ordinarily capped by a closure cap 13, as shown in Fig. 2. This outlet is customarily flanged as at 14, and the flange riveted to the bottom of the car 10, and the bolsters 11 ordinarily run longitudinally of the car as shown.

In order to effectively warm up the outlet 12, I provide a hood 15 made in any suitable manner, as from sheet metal, as shown, this hood being preferably double walled and having heat insulation between its walls, the lower end of the hood, in the form shown in Fig. 2, having a closed bottom and a drain cock 16 at its lower end. The upper end of the hood is enlarged as shown, and provided with a receiving groove in its upper surface to take the packing 17 which, when the device is in place, as shown in Fig. 2, bears against the flange 14, as here shown, although it might be arranged to bear against the bottom of the car and form a fluid tight joint. The upper end of the hood is surrounded by a supporting ring 18 which has radially extending lugs 19, into which lugs screw bolts 20 are threaded, the lugs being so proportioned that the bolts 20 rest upon the tops of the bolsters or girders 11, and when set up by a wrench or suitable tool, will force the hood 15 and the packing 17 into close contact with the flange 14, of the bottom of the car, and hold the hood firmly in position.

The hood is provided, at any suitable point, with an inlet 21, it being here shown as entering the side wall, and this inlet 21 can be coupled with any suitable source of steam or fluid heating medium. When the device is in place, as shown in Fig. 2, the steam will be turned on and the hood 15 filled with live steam, completely enveloping the outlet 12, and, by reason of the enlarged upper end of the hood, covering a considerable area of the bottom of the car. This will have the result of softening and melting the material in and about the outlet 12, and after that has been softened so that it will flow, the hood can be removed, and, upon taking off the cap 13, the contents of the car may be thoroughly drained.

If, during the application of steam, it should be desired to drain the products of condensation, the cock 16 can be opened so

as to free the hood of any collected liquids, or if it should be desired to have a flow of live steam through the hood during the heating of the outlet, the cock 16 may be turned 5 so as to vent the hood and permit a continuous flow of live steam.

If desired, the hood can be secured to the car so as to be always present by means of the chain 22 fastened at any suitable point

10 on the hood and to any suitable connection, as the eye 23, secured to the car frame.

In that form of the invention shown in Fig. 4, the same construction as shown in Fig. 2 and hereinbefore described will be 15 used, but I will obtain my heating supply for the hood from the internal heating pipes 24 of the tank car. The heating pipes 24 may, of course, be variously arranged in the car, the showing here being merely illustrative, and from such car heating pipes, I provide a valved connection 25 with a flexible member 26 which will couple with the hood 27. With this arrangement, it will be possible, by means of the valve 28, to keep 25 steam in the hood 27 during transportation so that the outlet from the car will be always in proper condition, and the flexible connection 26 will permit the removal of the hood when it is desired. Of course, if the hood 30 be not in place during transportation, it may be applied when the car is ready for draining, and the steam may then be turned on from the pipes 24 so as to warm up the hood and the outlet therein.

35 In the form of the invention heretofore described, it will be observed that the hood is quickly removable relative to the outlet. In the form of the invention shown in Fig. 5, a construction is shown in which semi-permanent securing of the hood in place is provided for. In this construction, the hood 29 is constructed identically with that form heretofore described, except that it is shorter than the outlet, and its bottom 30 terminates 45 at a point above the cap 31 of the outlet 32, the bottom 30 having an opening therethrough to permit the passage of the outlet 32, and this opening may be tightly sealed against the outlet, or, as shown in Fig. 5, 50 it may have a leakage area 33 to permit the steam coming through the inlet 34 and the products of condensation to seep out from the hood so that there will be live steam passing through the hood, and the steam issuing through the leakage passage 33 will pass upwardly and into contact with the bottom of the car, thus aiding in liquefying the contents of the car about the outlet.

55 If the bottom 30 be tightly sealed to the outlet, then there will be provided the drain cock 35, indicated in dotted lines to permit the products of condensation to be drawn off.

60 Where this type of hood is used, it will preferably be secured in place on the bolsters

or girders 36 by means of any suitable fastenings 37 engaging the radially projecting arms 38 extending from the top of the hood, so that the device will become a semi-permanent part of the car, although readily removable for repairs and replacement. The fastenings 37 may be loosened, the cap 31 removed from the outlet 32, and then the hood 29 may be readily taken off.

65 It is sometimes desirable to permit the steam to seep out so that a current of live steam will be passing through the hood, and the escaping steam rising beneath and about the bottom of the car will tend to warm the bottom of the car and the contents in the immediate vicinity of the outlet.

70 I have shown, in Fig. 6, a construction adapted to accomplish this result, in which the hood 39 is provided at a suitable point, in the present instance at its upper enlarged part, with an opening 40 which is controlled by a damper plate 41 suitably mounted so that it may be rotated to open and close the apertures 40, it being contemplated that a series of these apertures in sufficient number to permit the proper amount of steam to escape will be provided. With this arrangement and the damper control described, more or less steam may be permitted to pass through and out of the hood in close relation to the bottom of the car, and will materially aid in liquefying the contents.

75 It will be understood that such variations from the construction herein disclosed as involve mechanical skill and the use of other expedients equivalent of those herein shown and described may be made without departing 80 from the spirit of my invention.

85 I claim:

90 1. The combination with a tank car having an outlet extending downward from its body, and a removable closure for the lower end of said outlet, of a hood surrounding said outlet and forming therewith an annular chamber closed at its lower end, a fluid inlet extending through a wall of the hood, and means independent of the tank body and outlet for supporting the hood.

95 2. The combination with a tank car including a frame and having an outlet extending downward from its body, between members of the frame of the car, of a hood surrounding said outlet and forming therewith an annular chamber, a fluid inlet extending through a wall of the hood, and means detachably engaging the frame of the car at opposite sides of the hood for supporting it in position about the tank outlet.

100 3. A heating appliance for tank car outlets, comprising a hood adapted to be detachably positioned about an outlet of the tank body and, form therewith a heating chamber, a fluid inlet extending through a wall of the hood, and means projecting laterally from opposite sides of the hood for en-

gaging the car and supporting the hood about the outlet independent of any engagement between said means and said outlet.

4. In a heating appliance for tank car outlets, the combination of an open end hood having an enlarged open end adapted to be removably placed over an outlet, a sealing packing surrounding said open end, a closed bottom for said hood, a fluid inlet leading through a wall thereof, a drainage aperture in the bottom of said hood, and means for securing said hood to a car and forcing said packing against the car about said outlet.

5. In a heating appliance for tank car outlets, the combination of a double walled, open end hood adapted to be placed over an outlet, a packing at the upper end of said hood, a closed bottom for said hood, a fluid inlet leading through a wall thereof, and adjustable means for securing said hood in place and forcing said packing against the car about said outlet.

6. In a heating appliance for tank car outlets, the combination of a double walled, open end hood adapted to be placed over an outlet, a packing receiving groove at the open end of said hood, a sealing packing in said groove, a closed bottom for said hood, a fluid inlet entering through a wall thereof, arms extending laterally from said hood, and means carried by said arms to adjustably support said hood about said outlet and force said packing against the car.

7. In a heating appliance for tank car outlets, the combination of an open end hood adapted to be placed over an outlet and having double insulated walls, an enlarged upper end for said hood having a packing groove therein, a sealing packing in said groove, a closed bottom for said hood, a fluid inlet leading through a wall thereof, a supporting yoke having laterally extending arms secured to the top of said yoke, and screw bolts mounted in said arms and adapted to engage portions of a car to adjustably hold said hood in place and force said packing upwardly against the car about said outlet.

8. A heating appliance for tank car outlets, comprising an elongated hood closed at one end and having its opposite end open

and of greater diameter than the closed end, means extending laterally from the hood adapted to detachably engage a car frame and support the hood about a tank car outlet with the edge of its enlarged, open, end in contact with the tank, a fluid inlet extending through a wall of the hood, and a drain outlet extending through the closed end of the hood.

9. In a heating appliance for tank car outlets, the combination of a hood closed at one end and adapted to be placed over an outlet, means independent of the outlet and tank body for holding said hood in place with its open end in close contact with the car about said outlet, a fluid inlet in a wall of said hood and an adjustable fluid outlet in a wall of said hood to permit escape of fluid.

10. The combination of a hood closed at one end and adapted to be detachably positioned to enclose a tank car outlet with its open end in contact with the tank, said hood having an inlet and an outlet for a heating medium, and means for supporting said hood independently of the tank body and outlet and maintaining close contact between its open end and the tank about the outlet.

11. The combination with a tank car having an outlet extending downward from its body and provided with means normally preventing the flow of liquid therethrough, of a casing detachably positioned about said outlet to provide a heating chamber surrounding the vertical wall of the outlet and extending below and across the lower end thereof and having a fluid inlet extending through its wall.

12. The herein described attachment for tank cars comprising a hood-like casing, open at one end, whereby it may be positioned about a tank car outlet to form therewith a chamber surrounding such outlet and extending across the discharge end thereof, and means for detachably supporting said casing in position, a heating fluid inlet being provided in one of the walls of the casing.

In testimony whereof I have hereunto set my hand.

EDWARD A. FALL.
